DESIGN FOR A SPRAY GUN

Carl W. Sundberg, Birmingham, Mich., and Donald J. Peeps, Toledo, Ohio

Application June 13, 1942, Serial No. 107,186

Term of patent 7 years

To all whom it may concern:

Be it known that we, Carl W. Sundberg and Donald J. Peeps, citizens of the United States and residents respectively of Birmingham, in the county of Oakland, State of Michigan, and of Toledo, in the county of Lucas, State of Ohio, have invented a new, original, and ornamental Design for a Spray Gun, of which the following is a specification, reference being had to the accompanying drawing, forming a part thereof.

In the drawing, Figure 1 is a top plan view of a spray gun showing our new design; and Figure 2 is a side elevational view thereof.

We claim:

The ornamental design for a spray gun, substantially as shown.

CARL W. SUNDBERG.
DONALD J. PEEPS.
